CLAIM

The ornamental design for a wall light fixture as shown and described.

DESCRIPTION

FIG. 1 is a front view of a wall light fixture, showing the new design;

FIG. 2 is a rear view thereof;

FIG. 3 is a top view thereof;

FIG. 4 is a bottom view thereof;

FIG. 5 is a left side view thereof;

FIG. 6 is a right side thereof;

FIG. 7 is perspective front, top, right view thereof;

FIG. 8 is a perspective rear, top, right view thereof;

FIG. 9 is a perspective front, bottom, right view thereof; and,

FIG. 10 is a perspective rear, bottom right view thereof.

The broken lines in the figures show portions of the wall light fixture that form no part of the claimed design.

1 Claim, 5 Drawing Sheets
